SPARK PLUG

Arch E. Hornback, Chicago, Ill., assignor of one-half to Owen Van Dyke, Jr., Chicago, Ill.

Application April 18, 1938, Serial No. 202,624

7 Claims. (Cl. 123—169)

This invention relates to spark plugs for internal combustion engines.

One of the objects of the invention is to provide a spark plug in which the several parts are constructed and assembled within a shell in such manner that they will not be deleteriously affected by ignition of gas within the plug or by the combustion of gas in the engine cylinder in which the plug is mounted, and the sparking distances 10 between the central and intermediate electrodes and between the intermediate and shell electrodes will be constant.

Another object of the invention is to lessen the cost of production, particularly the cost of the 15 central electrode.

Another feature is the novel construction of the core on the central electrode and the mounting of the intermediate electrode thereon, whereby efficient sparking is produced.

20 Another object is to provide a plug which is quick heating and especially adapted for quick ignition when the engine is cold.

In the drawings:

Fig. 1 is a vertical sectional view, partly in elevation, of a spark plug embodying my invention.

Fig. 2 is an enlarged vertical sectional view of the lower part of the plug shown in Fig. 1.

Fig. 3 is a horizontal section on the line 3—3 of Fig. 2.

30 Fig. 4 is an enlarged vertical sectional view of the lower part of a modified form of the invention.

Fig. 5 is a horizontal section on the line 5—5 of Fig. 4.

Fig. 6 is a view, similar to Fig. 1, showing a modification.

Fig. 7 is a bottom plan view of the plug of Fig. 6.

In that embodiment of the invention shown in Figs. 1 to 3, inclusive, 10 indicates the shell of the spark plug, screw threaded at 11 and mounted in 40 a cylinder head 12. The shell 10 functions as an electrode. Preferably it is lined with a heat resisting alloy such as nichrome. An insulating core 13 of porcelain is mounted in the shell and surrounds a central electrode 14, which is of uniform diameter throughout its length, screw threaded at its upper end to receive the nuts 15, 16, and screw threaded at its lower end to receive the spark conducting disc 17 which is also threaded and after it has been screwed on said 50 electrode 14, the lower end 18 is upset so as to retain the disc 17 securely in place.

The core 13 has a central bore, the upper portion of which fits snugly around the central electrode 14, and the lower portion 19 of the bore is 55 slightly enlarged, whereby a shoulder 20 is

formed in the core 13. The central electrode 14 is provided with a horizontal aperture 21 for the purpose of retaining the end of a wire 22 which is wrapped around the electrode 14 to form a non-integral shoulder on the said electrode. Preferably I use an asbestos wrapping 23 in combination with the wire 22, said wrapping 23 serving as a packing between the wire shoulder 22 and the shoulder 20 of the core. When the nut 15 is screwed down on the upper end of the electrode 14 to bear on the core 13, the wire 22 and wrapping 23 on the electrode 14 are drawn up against the shoulder 20, whereby the parts are firmly held in assembled relation. A clamp nut 24 fits over the upper part of the core 13 and is screwed into the shell 10 as indicated at 25, a copper gasket 26 being positioned between the clamp nut 24 and core 13. Another gasket 27 is positioned between the shell 10 and core 13, and a gasket 28 is located between the shell 10 and cylinder wall 12. 20

The means for mounting an intermediate electrode 29 on the central electrode 14, between the core 13 and central electrode disc 17, will now be described. The intermediate electrode is indicated at 29 and as shown is in the form of a ring or centrally apertured disc of metal. It may be laminated or solid. An insulating disc 30 of mica is apertured to fit the central electrode 14 and rests on the central electrode disc 17. A smaller insulating disc 31 on the central electrode 14 fills 30 the space between the intermediate electrode 29 and the central electrode 14. Thus the intermediate electrode 29 is insulated from the central electrode 14 by the disc 31 and from the terminal disc 17 by the insulating disc 30. The space between the core 13 and the intermediate electrode 29 is occupied by the insulating core 32 preferably made of mica laminations. 35

The relative proportions of the shell, cores and electrodes are important. The internal diameter 40 of the shell is $\frac{11}{16}$ ", the diameter of the core 32 at its upper end where it abuts the core 13 is $\frac{1}{4}$ " and at its lower portion, just above the intermediate electrode 29, is $\frac{7}{16}$ ". The intermediate electrode 29 is also $\frac{7}{16}$ " in diameter, and the insulating disc 30 and central electrode terminal 17 are each $\frac{1}{16}$ " in diameter. From this it will be apparent that the gas chamber 33 is $\frac{5}{16}$ " in a radial direction at its widest portion and $\frac{1}{16}$ " in its narrowest portion opposite the intermediate electrode 29. The lower edge 34 of the shell 10 is approximately opposite the horizontal center of the intermediate electrode 29. The electrodes are made of heat resisting alloy such as nichrome or other suitable metal. 50 55

The spark gaps between the central electrode disc 17 and intermediate electrode 29 and between the intermediate electrode 29 and the shell electrode 10 remain constant at their predetermined 5 locations and proportions due to the construction described, the selection of materials and the careful proportioning of the several parts, whereby an extraordinarily efficient spark plug has been produced.

10 The elimination of an integral shoulder on the central electrode and the provision of the non-integral shoulder by means of the wire 22 and asbestos wrapping 23 not only reduces the cost of the electrode by elimination of milling operations, but has the further advantage of providing a slightly resilient bearing for the shoulder 20 of the core 13 which reduces breakage.

In the modification shown in Fig. 4, the several parts, with the exception of the insulating 20 core on which the intermediate electrode 29 is mounted, are the same as those described and shown in Figs. 1 to 3, inclusive. In the modification, said insulating core is made of mica and porcelain instead of mica alone. A porcelain 25 sleeve 35 surrounds the central electrode 14 from the upper surface of the disc 17 to the lower end of the core 13. Mica laminations centrally apertured to fit around the porcelain sleeve 35 are located above and below the intermediate 30 electrode 29, those between said electrode and the disc 17 being indicated at 36 and those above the intermediate electrode 29 being indicated at 37. The proportions are preferably as heretofore described.

35 The modified form of plug shown in Fig. 6 is the same as that shown and described in Figs. 1 to 3, inclusive, excepting that the lower edge 34 of the shell 10 is provided with a pair of stake wires 38. Each of said wires is integral with 40 or rigidly fastened in the lower edge of the shell, extending downwardly a short distance from opposite points on the shell edge as indicated at 39, 39 and then bent to lie in a horizontal plane and semi-circular form beneath the 45 shell edge but slightly spaced therefrom, each of said wires 38 terminating at the point 40 near the downturned part 39 of the other wire. The horizontal portions of the stake wires are approximately in the same horizontal plane as the 50 intermediate electrode 29. This construction provides a quick heating plug which is especially valuable for frequent cold startings of a motor.

Changes may be made in details of construction without departing from the scope of my invention.

55 It is to be understood that even though the plugs may be made larger than the standard size herein described, the spark gaps are preferably the same as those provided by electrodes of the described standard size.

I claim:

1. A spark plug comprising a shell which functions as an electrode, an insulating core in the shell, a central electrode mounted in the core, a 65 second insulating core mounted on the central electrode, and an intermediate electrode mounted on the second insulating core, the shell having a pair of semi-circular stake wires secured to and spaced from its lower edge, said stake wires 70 being disposed in a horizontal plane approximately the same as that of the intermediate electrode.

75 2. In a spark plug having a shell which functions as an electrode, an insulating core in the shell, a central electrode comprising a shaft of

uniform diameter, means on the upper end of the shaft for retaining the core, and a non-integral shoulder formed of slightly compressible material on the shaft, said insulating core being held on the central electrode in contact with 5 said shoulder and said retaining means, said shoulder consisting of a wrapping on the shaft, the shaft being apertured to retain the wrapping and prevent movement thereof longitudinally of the shaft.

10 3. In a spark plug having a shell which functions as an electrode, an insulating core in the shell, a central electrode comprising a shaft of uniform diameter, means on the upper end of the shaft for retaining the core, and a non-integral shoulder formed of slightly compressible material on the shaft, said insulating core being held on the central electrode in contact with 15 said shoulder and said retaining means, said shoulder comprising a wire and asbestos wrapping 20 on the shaft, the shaft being apertured to retain the wire and prevent movement longitudinally of the shaft.

25 4. In a spark plug having a shell which functions as an electrode, a central electrode screw threaded at each end, a spark conducting metal disc screwed on the lower end of the central electrode, the protruding end of said central electrode being upset against said metal disc for rigidly retaining it, an insulating disc of the 30 same diameter as the metal disc mounted on the central electrode above the metal disc, an insulating sleeve of smaller diameter than the insulating disc mounted on said central electrode above said disc, a metal ring constituting an 35 intermediate electrode mounted on the periphery of the insulating sleeve, and insulating material surrounding the central electrode between said intermediate electrode and the upper screw threaded end of the central electrode.

40 5. A spark plug comprising a shell which functions as an electrode, an insulating core in the shell, a central electrode mounted in the core, a second insulating core mounted on the central electrode, and an intermediate electrode 45 mounted on the second insulating core in a plane slightly below the lower end of the shell and slightly above the lower end of the central electrode, said central electrode terminating at its lower end in a spark conducting disc $\frac{1}{16}$ " in 50 diameter, the intermediate electrode being $\frac{1}{8}$ " in diameter, that part of the insulating core between said disc and intermediate electrode being $\frac{1}{16}$ " in diameter and that part above the intermediate electrode being $\frac{1}{8}$ " in diameter, 55 gradually diminishing to $\frac{1}{8}$ " diameter at its upper end, and the internal diameter of the shell being $\frac{1}{8}$ " whereby a restricted gas chamber is formed between said shell and said insulating core and electrode mounted thereon.

60 6. A quick heating spark plug comprising a shell which functions as an electrode, an insulating core mounted in the shell, the lower end of the core being spaced from the shell, a central electrode mounted in the core, a concentric disc 65 on the lower end of the central electrode, a second insulating core slightly spaced from the shell and mounted on the central electrode between said disc and first mentioned core, and a concentric ring which functions as an intermediate 70 electrode mounted on the second insulating core in a plane slightly below the lower end of the shell and slightly above the disc of the central electrode, the spark gaps between proximate electrodes being continuous circumferentially 75

and the space between the shell and said cores providing an air chamber within the shell having a restricted passage between the lower end of the shell and the second insulating core.

- 5 7. A quick heating spark plug comprising a shell which functions as an electrode, an insulating core mounted in the shell, the lower end of the core being spaced from the shell, a central electrode mounted in the core, a concentric disc 10 on the lower end of the central electrode, a second insulating core slightly spaced from the shell and mounted on the central electrode between said disc and first mentioned core, and a concentric ring which functions as an intermediate electrode mounted on the second insulating core

15 in a plane slightly below the lower end of the shell and slightly above the disc of the central electrode, said second insulating core being made of mica, and being of the same diameter as the intermediate electrode ring in that portion immediately above the ring, and of smaller diameter, equal to the disc on the central electrode, in that portion between the ring and disc, the spark gaps between proximate electrodes being continuous circumferentially and the space 10 between the shell and said cores providing an air chamber within the shell having a restricted passage between the lower end of the shell and the second insulating core.
